UNITED STATES PATENT OFFICE.

HENRY F. HERMAN, OF CHAPPAQUA, NEW YORK, ASSIGNOR TO STRAITLINE RADIO CORPORATION, OF NEW YORK, N. Y., A CORPORATION OF NEW YORK.

CABINET.

Application filed March 28, 1925. Serial No. 18,473.

This invention relates to cabinets, particularly adapted for use as a mounting and enclosure for radio receiving apparatus.

In radio receiving apparatus, it is essential that the different elements be mounted in fixed and rigid relation with the result that it is the universal practice to mount the different elements upon a mounting member and then build an enclosing structure or cabinet about the same with one wall releasably or hingedly connected whereby access may be had to the elements of the apparatus within the cabinet.

It is the object of the invention to provide an improved constructed and arranged cabinet for this purpose which is novel and cheap in structure and enhanced in appearance, and which has combined therewith a sound amplifier or horn built into and concealed within the cabinet.

In carrying out the invention, I provide a base board upon which the different elements of the apparatus are mounted in fixed position, and a hood to be engaged upon the base to enclose the apparatus carried by the base, said hood comprising end members and a panel bent to convex and preferably curved form in cross section interposed between the end members, with a sound amplifier or horn arranged and carried within the hood having a sound emitting outlet thereof through the end of the hood and a sound receiving opening within the hood in operative relation to a sound reproducing means forming a part of the receiving apparatus.

In the drawings accompanying and forming a part of this specification, I have shown a cabinet embodying my invention wherein Figure 1 is a plan view.

Figure 2 is a view looking at the front of the cabinet, the same being partly in elevation and longitudinal section.

Figure 3 is a cross sectional view taken on the line 3—3 of Figure 2 looking in the direction of the arrows.

Figure 4 is a cross sectional view taken on the line 4—4 of Figure 2 looking in the direction of the arrows.

Figure 5 is a perspective view of a bent panel engaged in the hood and co-operating

with the hood panel to form a sound amplifier or horn.

Figure 6 is a plan view of a portion of the mounting member to show the arrangement of audion mountings therein; and

Figure 7 is a sectional view of a portion of the mounting member taken on the line 7 of Figure 6 looking in the direction of the arrows.

Similar characters of reference designate like parts throughout the different views of the drawings.

In carrying out the embodiment of the invention shown in the drawing, there is provided a mounting member upon which the operative parts of a receiving apparatus is mounted, comprising a base board 8 of rectangular shape and of greater length than width having a perpendicularly arranged panel 9 secured thereto within one longitudinal edge portion, to constitute the front, said base board and panel being of non-conducting material.

A top, in the nature of a hood, is engaged upon the base to enclose the mechanism mounted thereon or the panel 9. This hooded top comprises a pair of end members or walls 10, 11 connected by a pair of rails 12, 13 interposed between the end walls and secured thereto as by angle brackets 14 with the rail 12 at the ends abutting at the lower rear corner of the end walls, and the bottom flush with the bottom of the end walls, while the rail 13 is at the front intermediate the top and bottom of the end walls, said rail being of greater width than thickness with the width of the rail arranged in a horizontal plane. A panel 15, preferably of wood veneer, is bent upon itself to form a U-shaped hood, said panel engaging in and closing the space between the end walls and rails. The panel is connected to the end members by engaging the ends in a groove or recess therein conforming to the shape to which said panel is bent, as shown at 16, with the opposite longitudinal edges of the panel engaging in grooves or recesses extending longitudinally of the rails 12, 13, as shown at 17 and 18.

Figures 3 and 4. In assembling the hood, the panel 15 is first engaged in the grooves in 100

the end members 10, 11 when the rails 12, 13 are adjusted with the longitudinal edges of the panel engaging in the rail grooves when the rails and ends are secured together, as by 5 the angle brackets 14. By this arrangement, the panel is held firmly in place and prevented from becoming warped and distorted from climatic conditions when made of wood veneer. The hood comprising the connected 10 end members and panel is engaged over the base board 8 and panel 9 with the ends 10, 11 engaging at the ends of the panel 9 and the forward edge portion of the rail 13 seated in an angular portion of the panel 9, as at 15 19, forming in effect a shelf extending forward of the panel 9. By this arrangement, the hood is adapted to be removably mounted upon the base and held against endwise or forward shifting movement on the base, and 20 to position the hood and prevent lateral movement, suitable means may be arranged on the mounting members to engage in recesses or openings in the hood rail 12 and bottom of the ends 10, 11. However, the hood is prefer- 25 ably connected to the base to be swung upwardly and rearwardly from the mounting members for which purpose the hood is hingedly connected to the mounting member or base, as shown at 20.

30 As stated it is also an object of the invention to combine with the cabinet a sound amplifier built thereinto to be enclosed and concealed thereby. For this purpose, an end wall of the hood, in the present instance the 35 end 11, is arranged with an opening 21 (Figures 2 and 4).

A panel 22 of trapezium form and preferably of wood veneer is bent longitudinally upon itself to substantially U-shape in cross 40 section, as shown in Figure 5, with the opposite longitudinal edges extending substantially in parallel relation. The panel in this form is inserted into the hood through the opening 21 with the edge at the smaller end 45 in abutting relation to the end wall 10, as at 23, where it is supported by a bracket 24 fixed to said end with the edge at the larger end seated in a recess arranged about the opening 21, as at 25, and the opposite marginal portions lying in contiguous relation to the inner 50 surface of the hood panel 15, as at 26, and in conjunction with said hood panel forming a sound amplifier or resonance chamber within the cabinet. The larger opening at the one 55 end of said chamber constitutes the outlet, while the sound receiving inlet to said chamber is through an opening 27 in the smaller end of the panel in register with an opening in the supporting bracket 24 with which a 60 tubular arm 28, preferably of tapered form, communicates, the end of larger diameter of said arm engaging in the opening of bracket 24 and retained therein by a wedge 29 inter- 65 posed between the arm and the cabinet end 10. This arm extends in a direction toward

the larger end of the panel 22 to adjacent midway between the ends of the cabinet where it is connected to a sound reproducing unit, usually termed a loud speaking unit, shown in a general way at 30, attached to the under- 70 side of the shelf or rail 13, said unit having an adjusting button 31 for the diaphragm thereof extending through an opening in said shelf.

To deflect and modulate the sound emitted from the amplifier, a deflector 32 is adjustably mounted on the outer side of the end wall 11 to be positioned to deflect sound waves in a direction toward the front of the cabinet. This deflector is in the form of a plate having a surface 33 adjacent the outlet of the amplifier chamber of concave form, and is pivotally or hingedly mounted, as at 34, on the end wall 11 to have movement on a vertical axis. This deflector may also serve as a closure for the horn to prevent accumulation of dust, etc. therein, and retained in closed position by a latch 35. It will be obvious that should the deflector be moved to its entirely open position that the sound will be emitted in a direction longitudinally of the amplifier, while should the deflector be adjusted to a partly open position the sound waves will impinge against the concave surface 33 and be deflected in a direction in which said surface 95 extends, and also that the sound may be modulated by the extent to which the deflector is positioned away from the outlet of the amplifier.

As stated, the base board is in the nature of a mounting member upon which the operative parts of a receiving apparatus are mounted, and to facilitate the mounting of electron tubes 36, (Figures 6 and 7) said base is provided with perforations 37, shown in the present instance as three in number, to serve as receiving sockets for said electron tubes with contact terminals for electric conductors in the form of spring fingers 38 fixed in a recess within the under surface of the base board 100 and disposed about said opening in predetermined position and extending radially toward the center of the perforations for engagement of contact pins projecting through the base of the electron tubes, as shown in Figure 7, 115 the electric conductors connected to the contacts 38 being arranged in recesses 39 in the under surface of the base board and the latter being provided with perforations 40 for the passage of such conductors for connection of the electron tubes with other elements of the apparatus mounted upon the base board. To retain the contacts of the electron tubes in electrical connection with the contact fingers 38, sleeves 41 of insulator material, such as 120 bakelite, are fitted in the perforations 37, the movement of said sleeves into the openings being limited by the contact fingers, and the sleeves arranged with angle slots, as shown at 42, for the engagement of the usual pin ex- 125 130

tending laterally from the base of electron tubes.

The rail or shelf 13 is arranged with a series of alined perforations 43 for the passage of knobs 44 connected to adjustable parts of the apparatus, such as rheostats, condensers, etc., certain of said knobs having graduated dials, shown in dotted lines at 45 in Figure 1, connected thereto and arranged below the shelf when the hood is in closed position and the graduations of which dials are adapted to be observed through further openings 46 in said shelf.

It will be obvious that various modifications may be made in construction and arrangement of parts, and that portions of the invention may be used without others and come within the scope thereof.

Having thus described my invention I claim:

1. In a cabinet for radio receiving apparatus, a mounting base for the apparatus, and a removable top for the base comprising end members, rails to connect and maintain the end members in spaced relation, and a panel of concave form interposed between and connected at the marginal portions to the rails and ends to form a hood.

2. In a cabinet for radio receiving apparatus, a mounting base, a hood engageable with the base, and a panel within and cooperating with the hood to form a resonance chamber having a sound emitting outlet through the end of the hood and a sound receiving inlet from within the hood.

3. In a cabinet for the purpose specified, a mounting base, a hood engageable with the base including end members, one of said end members having an opening, and an intermediate panel of concave form interposed between the end members, and a closure for the opening in the one end.

4. In a cabinet for the purpose specified, a mounting base, a hood engageable with the base including end members, one of said end members having an opening, and an intermediate panel of concave form interposed between the end members, a panel within the hood arranged to cooperate with the intermediate panel to form a conical resonance chamber having the larger end at the opening in the one end of the hood, and a closure for the opening in the other end member supported to have adjustment on a vertical axis, the surface of said closure adjacent the opening being of concave form.

5. In a cabinet for the purpose specified, a mounting base, and a hooded top for the base hingedly connected thereto comprising end members, intermediate connecting members, and an intermediate panel bent to curved form in cross section and mortised at the edges in the said end members and intermediate connecting members.

6. In a cabinet for the purpose specified, a

mounting base having an upright panel fixed thereto adjacent the front edge, and a hooded top for the base comprising end members, a pair of rails interposed between and connected to said end members, hinge means connected to one of said rails and the base to hingedly connect the hood with the base, the other of said rails being arranged to have a mating connection with the base panel, and a panel bent to curved shape in cross section interposed between the end members and connecting rails with the edge portions fitted in grooves in said end members and rails.

7. In a cabinet for the purpose specified, a mounting base, a hood engageable with the base having an opening in one end, and a horn arranged in and extending longitudinally of the hood having the sound emitting outlet thereof at the opening in the hood end and the sound receiving opening thereto within the hood.

8. In a cabinet for the purpose specified, a mounting base, a hood engageable with the base having an opening, and a panel arranged within the hood to form a horn having the sound emitting outlet thereof at the opening in the hood and the sound receiving opening within the hood, and a deflector adjustably mounted at the opening in the hood and adapted to serve as a closure for said opening.

9. In a cabinet for the purpose specified, a base board, a panel fixed to the base board at a marginal portion to extend at a right angle thereto, and a hood engageable with the base board having end members extending at a right angle to the base board, a rail interposed between and connected to the end members at the corner formed by the rear edges and bottoms of the end members, a shelf interposed between and connected to the end members at the forward edges and intermediate the top and bottom of the end members and adapted to have a mating connection with the base panel and having a series of perforations arranged therein, a panel bent to curved shape in cross section interposed and closing the space between the end members, rail and shelf, and a hinge connected to the rail of the hood and base board to connect the hood to the base board.

10. A cabinet in accordance with claim 9, wherein a resonance chamber is arranged within the hood having an outlet at one end of the hood and a sound receiving opening within the hood.

11. A cabinet in accordance with claim 9, wherein the one end of the hood has an opening therein, a panel of trapezium form bent longitudinally upon itself and arranged within the hood to co-operate with the hood panel to form a conical resonance chamber having the larger end supported at the opening in the one hood end and supported at the smaller end at the opposite end of the hood with a sound receiving opening in said end,

and a tubular arm mounted in the hood with one end in communication with the inlet of the resonance chamber and extending in parallel relation to said chamber with the opposite end in communication with a sound reproducing device mounted on the inner side of the shelf.

12. A cabinet in accordance with claim 9,

wherein the base board is arranged with perforations and channels in the under surface 10 in communication with said perforations.

Signed at New York city, in the county of New York and State of New York, this 23rd day of March, 1925.

HENRY F. HERMAN.
